UNITED STATES PATENT OFFICE.

MARIE ROSE DURANTE, OF UTICA, NEW YORK.

DESIGN FOR A COUGH TABLET.

Application filed February 23, 1922. Serial No. 842. Term of patent 14 years.

To all whom it may concern:

Be it known that I, MARIE ROSE DURANTE, a citizen of the United States, residing at Utica, in the county of Oneida and State of New York, have invented a new, original, and ornamental Design for Cough Tablets, of which the following is a specification, reference being had to the accompanying drawing, forming part thereof.

Fig. 1 is a view of one side of the tablet; Fig. 2 is a view of the opposite side of said tablet.

I claim:

The ornamental design for a cough tablet, as shown.

In witness whereof I have hereunto set my hand.

MARIE ROSE DURANTE.
